UNITED STATES PATENT OFFICE.

FRANK P. MIES, OF CHICAGO, ILLINOIS, ASSIGNOR TO PLURAL SYSTEM
VENTILATOR CO.

ELECTRIC HEATER.

1,038,410.

Specification of Letters Patent. Patented Sept. 10, 1912.

Application filed January 10, 1910. Serial No. 537,260.

To all whom it may concern:

Be it known that I, FRANK P. MIES, a citizen of the United States, residing at Chicago, in the county of Cook and State 5 of Illinois, have invented certain new and useful Improvements in Electric Heaters, of which the following is a specification.

My invention relates to improvements in thermo-electric devices and more particularly to devices of this character designed 10 to heat air that may be brought into contact with the surfaces thereof.

One of the objects of my invention is to provide an electric air-heating device having 15 a maximum of surface of the heating medium presented to the direct action of the air.

Another object of my invention is to provide an air-heating device wherein the 20 surface of the heating medium is increased substantially in proportion as expansion of the air is increased due to the increased temperature thereof, as the air passes through the device.

Still another object of my invention is to provide a device of the character described 25 that is highly efficient, cheap in construction, durable, and not deranged by expansion of the heating medium.

Other and further objects of my invention 30 will become apparent to persons skilled in the art from the description and drawings, in which—

Figure 1 is an elevation of one of my 35 heating units with part of the casing broken away to show the heating medium; Fig. 2 is an enlarged elevation showing a fragment of the heating medium on one side of the vertical axis partly in section; Fig. 3 is a 40 cross sectional view taken on line 3—3 of Fig. 2; Fig. 4 is a fragmentary sectional view taken on line 4—4 of Fig. 3; and Fig. 5 is a section on line 5—5 of Fig. 4.

In all of the views the same reference 45 characters indicate similar parts.

The heater consists of a continuous electric conductor, such as a wire, ribbon, or similar heating medium wound upon substantial supports and providing spaces for free 50 circulation of air in contact with a maximum surface of the heating medium. The general form of the device is that of a truncated cone, as shown in Fig. 1, the heating medium being contained within a casing 55 open at each end.

In the embodiment illustrated, 10 is the upper supporting structure consisting of a plurality of concentric rings, 11, 12, 13, and 14. The lower supporting structure 15 is of similar but larger diameter composed of 60 rings, 16, 17, 18, and 19. The rings of each structure are held together by interconnecting radial arms, 20. The rings are preferably made of some insulating and substantially non-combustible material, such as 65 enameled iron. The rings are notched, as shown at 21, at intervals for the reception of the wire-bearing supporting parts 22. The wire-bearing supports are provided with a series of lateral grooves, 23, for receiving 70 and retaining individual wires. The bars 22 are provided with ribs, 24, to give strength with a minimum of material. The ribs are notched, near each end, as at 25, for the reception of the respective rings, 10—15. 75 The rings and supporting bars are preferably made of iron and then covered with an enamel so that any wires wound thereon will not come into metallic contact with the supporting structure. 80

The rings, 10 and 15 are securely fixed a proper distance apart. The bars of the inner ring, of which there is shown to be six, are laid in place so that the notches in said bars will fall in the notches in said rings. The rings and bars are thereby held against relative axial movement, as plainly shown. The heating medium or wire, 26, is then wound tightly over said bars and in the lateral grooves, 23, provided therein. These 90 grooves are as close together as may be to prevent contact of adjacent turns of the wires. When the wires are wound around the bars, they are thus prevented from moving radially and being restrained from movement in other directions, by the notches, they are firmly retained in place. After one layer of wire has been wound in the grooves of the inner series of bars, another series of bars are placed in the notches of the ring, 12, and the heating medium wound around them in the same manner. In turn the bars are thus secured to rings 95 13 and 14. The heating medium may thus be wound around all of the bars without severing said medium and all of the bars will thereby be securely held in place. The grooves 23 are sufficiently deep to retain the heating medium after it has become expanded by the application of heat. 26* and 110

26^b, the ends of the heating medium, form the electrical terminals of the device. Their terminals may be arranged for ready connection to the circuit in any convenient 5 manner. The heating medium thus described may be contained within a jacket or casing, 27, and when air is forcibly projected through the device, it should preferably enter the smaller end and leave at the 10 larger end.

When the air is cool, it occupies smaller space than when expanded by the heat and as the air passes through the device the cross section of its path correspondingly 15 increases with the increase of temperature and the superficial area of the heating medium increases as the air progresses toward the larger end. By this means the air is confined and retained in contact with the 20 heating medium and the resistance to its movement through the device is retained at a minimum.

When natural circulation is to be depended upon to move the air through the device, 25 the larger end should be above and the smaller end below. The air as it becomes heated will move out and upwardly from the larger end and colder air will be drawn into the smaller end, thereby forming a 30 strong induced draft of air.

The moving air through the device will come in contact with practically the entire surface of the heating medium and will absorb most of its heat directly therefrom, but 35 as the air also comes in contact with all of the supporting structure it will absorb the heat that may be imparted to such structure by the heating medium.

While I have thus described in some detail 40 a single embodiment of my invention, it will be understood that such particular embodiment is only one which I have chosen from numerous others as the preferred construction, and I do not, therefore, limit my invention to the precise structure described 45

further than is specified in the following claims.

What I claim is:

1. A heating device comprising an upper supporting member having a plurality of 50 concentric rings and radial arms connecting said rings, a lower supporting member having a like plurality of concentric rings of relatively larger diameter and radial arms connecting said rings, bars extending between said upper and lower supporting members, and engaging the exterior edges of said rings at regular intervals around the peripheries thereof, and a continuous unbroken wire wound successively upon the 60 concentric truncated-cone structures so formed.

2. In a heating device of truncated-cone shape, an upper and a lower structure each having a plurality of concentric rings and 65 radial connecting arms, the rings of the lower structure being greater in diameter than corresponding rings of the upper structure, separable interchangeable bars having notches near their ends, said rings 70 having on their outer edges coacting notches at frequent intervals around their peripheries, whereby bars may be placed upon the innermost rings of both upper and lower structure, held vertically by said coacting- 75 notch engagement and radially by a wire to be wound therearound to constitute a heating medium, successive rings subsequently to be similarly connected by bars and the bars similarly bound by wire, and a wire so wound upon the device to form concentric, truncated-cone shaped, heating members included in the space defined by the ring of largest diameter.

In testimony whereof I hereunto set my 80 hand in the presence of two witnesses.

FRANK P. MIES.
